UNITED STATES PATENT OFFICE.

EDWARD E. BUSTER, OF PORTLAND, OREGON.

SILO-DOOR SUPPORT.

1,190,720.

Specification of Letters Patent. Patented July 11, 1916.

Application filed April 29, 1915. Serial No. 24,779.

To all whom it may concern:

Be it known that I, EDWARD E. BUSTER, a citizen of the United States, residing at Portland, in the county of Multnomah and State of Oregon, have invented a new and useful Silo-Door Support, of which the following is a specification.

This invention relates to a door support for use in connection with silos and the like, the principal object of the invention being to provide a single hinge structure shiftable readily to position adjacent any one of the doors of a silo and adapted to be connected to said door to support it when swung open, thus obviating the necessity of utilizing a separate hinge for each door and, consequently, materially reducing the cost of the silo.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front elevation of a portion of a silo having the present improvements combined therewith. Fig. 2 is a section on line A—B Fig. 1. Fig. 3 is a section on line C—D Fig. 2. Fig. 4 is a perspective view of the slidable hinge member. Fig. 5 is a perspective view of a bearing or support which may be provided at the lower end of the hinge guide. Fig. 6 is a perspective view of a form of holding bracket designed to be used in connection with the hinge and guide. Fig. 7 is a perspective view of the upper guide holding bracket. Fig. 8 is a perspective view of one of the hinge engaging brackets carried by each door.

Referring to the figures by characters of reference 1 designates a portion of a silo structure provided with superposed doors 2 of any desired construction and which doors may be provided with any suitable means for securing them in closed positions. Heretofore it has been necessary to provide each door with its own hinges and, as here-

inbefore stated, it is the object of the present invention to obviate this expense by utilizing a single hinge structure which can be employed in connection with all of the doors.

Arranged upon the outer face of the silo structure 1 adjacent one side of each of the doors 2 are preferably two brackets 3 each of which includes a substantially horizontal portion 4 provided with an opening 5 which intersects the front edge of the bracket as shown particularly in Fig. 6. Pivotedly mounted on each bracket is a hook-like member 6 constituting retaining means and which member is adapted to swing across the front of the opening 5. The various brackets 3 are disposed in vertical alignment and extending centrally through all of the openings 5 is a guide member 7 which can be in the form of a rod, cable or the like, the ends of which are secured in any preferred manner to the silo structure adjacent the top and bottom thereof. In the drawings a rod has been shown, the upper end of the rod extending into an opening 8 formed within a bracket 9 secured to the silo structure, while the lower end of the rod bears upon a bracket 10 secured to the lower portion of the silo structure. Obviously, however, the lower end of the rod could be mounted on the foundation of the silo and secured to it in any desired manner, as will be apparent. In order to prevent the rod from pushing upwardly within the bracket 9, a sleeve 11 is preferably mounted on the upper portion of the rod and is held thereto by a set screw 12 or the like which fits close to the bracket 9. This sleeve operates to hold the rod 7 against upward movement.

Slidably mounted on the guide 7 is a sleeve 13 the length of which is somewhat greater than the distance between the brackets 3 of each pair. This sleeve may have a set screw 14 for engaging the guide to hold the sleeve against longitudinal movement. The sleeve is interposed between eyes 15 arranged at one end of angular arms 16, these arms being connected by braces 17 whereby a rigid angular frame is provided. Those ends of the arms 16 remote from the eyes 15 are pivotally engaged by links 18 adapted to swing horizontally, the links being preferably connected by a bar 19 so that they will move together. Each link is preferably made up of spaced strips 20 the free ends

of which are formed with alining openings 21. The spaces 22 between the strips of the links are adapted to receive the outstanding portions 23 of brackets 24 which are secured to each door 2. A pair of these brackets is mounted on each door and the two brackets are spaced apart a distance equal to the distance between the links 20 so that said links can be readily brought into engagement with both brackets on a door. The outstanding portions 23 of the brackets have openings 25 adapted to register with the openings 21 so that, by inserting a rod 26 downwardly into the openings 21 and 25, the links 20 will be pivotally connected to the door 2.

It is to be understood that the hook-like members 6 serve to prevent the guide 7 from springing out of the opening 5 within the brackets 3. When it is desired to use the door supporting attachment for the purpose of swinging open one of the doors of the silo, the set screw 14 is loosened and the hook-like members 6 in the path of the sleeve 13 are swung to open positions, as shown in Fig. 6 so that said sleeve 13 together with the eyes 15 and the arms 16 can be moved along the guide 7 until sleeve 13 is brought into the openings 5 in those brackets 3 beside the door to be opened. When the sleeve is thus positioned, it is fastened in place by means of the set screw 14 and will fit snugly within the openings 5, the outstanding portions 4 of the brackets serving to hold the sleeve against horizontal displacement relative to the brackets while the set screw 14 holds the sleeve against upward or downward movement. The arms 16 and links 18 are shifted toward the door and the outstanding portions 23 of brackets 24 on the door are received within the spaces 22 after which rod 26 is inserted through the registering openings 21 and 25. Consequently the door can thus be swung inwardly and laterally. After the door has been swung back to its closed position and secured, the door supporting structure can be detached therefrom by removing rod 26, after which the said door supporting structure can be adjusted longitudinally along the guide 7 to position opposite the next door to be swung open, whereupon the operation hereinbefore described can be repeated.

It is to be understood that the means for connecting the door to the guide 7 can be modified. Furthermore, while the door supporting structure can, if desired, remain a permanent fixture of one silo, it can also, by reason of its detachability, be transported from one silo to another so that one of said door supporting structures can thus be used in connection with a group of silos.

What is claimed is:—

1. The combination with a silo having a plurality of superposed doors, of a hinge

structure adjustable into position adjacent any one of the doors, and means for detachably connecting said hinge structure to said doors.

2. The combination with a silo having a plurality of superposed doors, of a vertically adjustable hinge structure upon the silo, means upon the silo for engaging the hinge structure to hold it against displacement after adjustment, and means for detachably connecting the hinge structure to the adjacent door. 75

3. The combination with a silo having superposed doors, of a bracket upon the silo and adjacent each door, a hinge structure 80 adjustable into engagement with any one of the brackets, said bracket constituting means for holding the hinge structure against horizontal displacement, and means for detachably securing the hinge structure 85 to the adjacent door.

4. The combination with a silo having superposed doors, and a bracket adjacent each door and upon the silo, of a hinge 90 structure including a sleeve shiftable into position within any one of the brackets, a frame movable with the sleeve and adapted to swing relative thereto, and means carried by the frame for detachable connection with the adjacent door. 95

5. The combination with a silo having superposed doors, of a guide upon the silo and adjacent the doors, a hinge structure adjustable along the guide, and means for detachably connecting the hinge structure 100 to the adjacent door.

6. The combination with a silo having superposed doors, of a guide detachably connected to the silo, a hinge structure adjustable along the guide to position adjacent any one of the doors, and means for detachably connecting the hinge structure 105 to the adjacent door.

7. The combination with a silo having superposed doors, and brackets upon the 110 silo and adjacent the respective doors, said brackets having alining openings, of a guide extending through the openings and connected to the silo, a hinge structure adjustable along the guide to position within 115 any of the brackets, and means for detachably connecting the hinge structure to the adjacent door.

8. The combination with a silo having superposed doors, and brackets upon the 120 silo and adjacent the respective doors, said brackets having alining openings, of a guide extending through the openings and connected to the silo, a hinge structure adjustable along the guide to position within 125 any of the brackets, means for detachably connecting the hinge structure to the adjacent door, and means upon one of the brackets for holding the guide in position 130 within the brackets.

9. The combination with a silo having superposed doors, and brackets upon the silo and adjacent the respective doors, said brackets having alining openings, of a guide extending through the openings and connected to the silo, a hinge structure adjustable along the guide to position within any of the brackets, means for detachably connecting the hinge structure to the adjacent door, and means upon one of the brackets for holding the guide in position within the brackets, said means being shiftable to permit the passage of the hinge structure through the brackets.
10. The combination with a silo having superposed doors, of brackets secured to the silo and adjacent the doors, said brackets having vertically alining openings, a guide secured to the silo and extending through the openings, a sleeve adjustable along the guide and into any one of the openings, the said brackets when engaged by the sleeve constituting means for holding the sleeve against horizontal displacement, a hinge structure mounted to swing upon the guide and held against vertical movement independently of the sleeve, means for securing the sleeve to the guide, and means for detachably connecting the hinge structure to the adjacent door.
15. 10. The combination with a silo having superposed doors, of brackets secured to the silo and adjacent the doors, said brackets having vertically alining openings, a guide secured to the silo and extending through the openings, a sleeve adjustable along the guide and into any one of the openings, the said brackets when engaged by the sleeve constituting means for holding the sleeve against horizontal displacement, a hinge structure mounted to swing upon the guide and held against vertical movement independently of the sleeve, means for securing the sleeve to the guide, and means for detachably connecting the hinge structure to the adjacent door.

In testimony that I claim the foregoing as my own, I have hereto affixed my signature in the presence of two witnesses.

EDWARD E. BUSTER.
